Primary Examiner — John R Yeh(74) *Attorney, Agent, or Firm* — Derek Fahey, Esq.; The Plus IP Firm, PLLC(57) **CLAIM**

The ornamental design for a cleaning device with a microphone shaped end, as shown and described.

DESCRIPTION

FIG. 1 is a first perspective view for a cleaning device with a microphone shaped end having a cleaning part attached; FIG. 2 is a second perspective view without the cleaning part attached;

FIG. 3 is a first side view thereof;

FIG. 4 is a second side view thereof;

FIG. 5 is a front view thereof;

FIG. 6 is a rear view thereof;

FIG. 7 is a top view thereof; and,

FIG. 8 is a bottom view thereof.

The cleaning part shown in FIG. 1 is directed to environment of the cleaning device with a microphone shaped end and forms no part of the claimed design. The other broken lines in the drawings depict portions of the cleaning device with a microphone shaped end that form no part of the claimed design.
